VACUUM PUMPING APPARATUS

Judd H. Black and Horace G. Warren, Rochester,
N. Y., assignors to Eastman Kodak Company,
Rochester, N. Y., a corporation of New Jersey

Application September 1, 1950, Serial No. 182,862

3 Claims. (Cl. 230—101)

1

This invention relates to apparatus for producing vacuum and is particularly concerned with vacuum pumps of the type wherein organic pump fluid vapors are passed through paired ejector and diffuser elements and condensed.

It is an object of this invention to provide improved apparatus for producing vacuum.

It is a further object of this invention to provide improved ejector pumps of the type employing organic pump fluid vapors for evacuation in the high vacuum range.

Another object of the invention is to provide a high vacuum pump of the ejector type having a more compact structure than obtainable when spent pump fluid is returned to the pump boiler by gravity flow alone.

Another object of the invention is to provide a high vacuum pump of the ejector type having no movable parts ordinarily subject to mechanical failure.

Another object of the invention is to provide a high vacuum ejector pump including positively-acting means for returning condensed organic pump fluid to the boiler against pressure in the boiler.

Another object of the invention is to provide a high vacuum pump of the ejector type including means for returning condensed pump fluid from the paired ejector-diffuser elements to the boiler of the pump against pressure in the boiler, which means is responsive to changes in the pressure in said boiler.

Another object of the invention is to provide means for positively impelling condensate from the ejector-diffuser assembly to the boiler of a high vacuum pump without increasing the power consumption of the pump to an objectionable degree.

Another object of the invention is to provide a high vacuum ejector pump of the type employing organic pump fluid and including means for utilizing a portion of the pump fluid vapors to return condensed pump fluid from the pumping zone of the pump to the boiler against boiler pressure and at the same time to preheat such condensed pump fluid before return to the boiler.

Other objects will be apparent from the drawing and from the description and claims which follow.

These and other objects are attained by means of this invention which is described hereinafter with reference to a preferred embodiment as illustrated in the drawing. The single figure of the drawing is a view in elevation, partly broken away and in section, of a high vacuum

2

ejector pump embodying the invention in a preferred form.

Vacuum pumping apparatus embodying this invention is of the type wherein vapors of organic pump fluid produced in a suitable boiler are passed through paired ejector and diffuser elements, condensed and returned to the boiler, the pump fluid vapors exerting a pumping action by passage through the paired ejector and diffuser elements whereby a system connected to the pumping apparatus is evacuated.

In the preferred embodiment of the invention as illustrated in the drawing, the vacuum pumping apparatus comprises pumping means adapted to be connected to the system to be evacuated, vapor-generating means connected to the pumping means for delivering vaporized pump fluid to said pumping means, and condensate return means connecting said pumping means with said vapor-generating means.

The pumping means of the preferred apparatus comprises a diffuser element 10 and an ejector element 11 arranged in pumping relation with the nozzle of ejector element 11 directed into the throat of diffuser element 10. A condenser coil 12 connected to a source of cooling fluid (not shown) is positioned around the diffuser element 10 in heat conducting relation therewith, coil 12 extending around at least the portion of diffuser element 10 remote from ejector element 11 and preferably around element 10 substantially throughout the length of element 10.

The vapor-generating means comprises a boiler 13 spaced below the pumping means and adapted to contain a body of organic pump fluid, such as a phthalate ester or sebacate ester or the like, and including a suitable heater element 14 such as an electrical immersion heater or other conventional heating means. Boiler 13 is connected to ejector element 11 of the pumping means by primary vapor conduit 16, conduit 16 being of sufficient diameter to permit unrestricted flow of pump vapors from boiler 13 to ejector element 11.

The condensate return means comprises a generally vertically disposed diffuser tube 17 positioned between the pumping means and boiler 13, a condensate conduit 18 connecting diffuser element 10 with the upper end of diffuser tube 17, a second condensate conduit 19 connecting the lower end of diffuser tube 17 with boiler 13, a jet nozzle 21 directed downwardly into the throat of diffuser tube 17, and a secondary vapor conduit 22 connecting jet nozzle 21 with primary vapor conduit 16 at a point along primary vapor

conduit 16 between boiler 13 and ejector element 11.

In the preferred embodiment, diffuser element 10 in accordance with conventional construction practices is flared at the low pressure end of the element 10 adjacent ejector element 11 and is convergent from the low pressure end toward a constricted throat and thence divergent at the high pressure or exhaust end of diffuser element 10. Diffuser element 10 includes an inlet port 23 at the low pressure end of the diffuser element 10, which port 23 is adapted to be connected to the system to be evacuated. An outlet or exhaust port 24 at the high pressure end of diffuser element 10 is arranged for connection to a mechanical backing pump.

Ejector element 11 is of conventional design and is connected to primary vapor conduit 16 in the low pressure end of diffuser element 10, the ejector element 11 being constricted adjacent the primary vapor conduit 16 and thence flaring to the mouth of ejector element 11 directed towards the constricted throat of diffuser element 10. Inlet port 23 opens into diffuser element 10 at a point behind the mouth of ejector element 11 whereby backstreaming of pump fluid vapors into the space being evacuated is minimized.

Referring to the condensate return means, diffuser tube 17 comprises a downwardly convergent upper portion, a constricted throat and a downwardly divergent lower portion. Jet nozzle 21, which is preferably flared outwardly to the jet mouth, is directed downwardly into the convergent upper portion of diffuser tube 17 towards the constricted throat of diffuser tube 11. Condensate conduit 18 connecting diffuser element 10 and diffuser tube 17 opens into the upper end of diffuser tube 17 at a point not lower than the mouth of jet nozzle 21. In the preferred embodiment wherein diffuser element 10 is generally horizontally disposed and cooled by condenser coil 12 substantially throughout its length, condensate conduit 18 is branched and connected to both ends of diffuser element 10. Secondary condensate conduit 19 connecting the lower end of diffuser tube 17 with boiler 13 desirably opens into boiler 13 below the normal level of pump fluid in the boiler 13.

The secondary vapor conduit 22 connecting jet nozzle 21 with the primary vapor conduit 16 is desirably of substantially smaller diameter than the primary vapor conduit 16. In order to conserve heat, boiler 13, primary vapor conduit 16 and secondary vapor conduit 22 are lagged throughout their extent as indicated at 28, 28. Drain cap 26 on boiler 13 provides means for draining pump fluid from the boiler. If desired, a manometer 27 can be connected to the boiler 13 and diffuser element 10 for measuring the boiler pressure.

In operating the preferred apparatus illustrated in the drawing, inlet port 23 is connected to the system to be evacuated and exhaust port 24 is connected to a suitable backing pump such as a mechanical pump or the like. Cooling fluid is circulated through the condenser coil 12. A suitable organic pump fluid such as phthalate ester, sebacate ester, tetrasilane or other well-known pump fluid is progressively vaporized in boiler 13 by means of heater element 14. Pump fluid vapors generated in the boiler are channeled upwardly through primary vapor conduit 16 to ejector element 11. The vapors are ejected through the mouth of ejector element 11, pass through the constricted throat of diffuser ele-

ment 10 and expand into the divergent high pressure end of diffuser element 10 thereby evacuating the system connected to inlet port 23.

During passage through diffuser element 10, the vapors are cooled by conduction from condenser coil 12 and condense in the diffuser element 10. In order to ensure substantially complete condensation of the pump fluid vapors, diffuser element 10 is cooled substantially throughout its length whereby substantially only the non-condensable gases drawn into the pump through inlet port 23 are exhausted through exhaust port 24.

Condensed pump fluid in diffuser element 10 flows downwardly through condensate conduit 18 to diffuser tube 17. In diffuser tube 17 the condensate is impelled by the pump fluid vapors which are conducted from the primary vapor conduit 16 to jet nozzle 21 by secondary vapor conduit 22, such vapors being passed with the condensate downwardly through diffuser tube 17. The vapors issuing into diffuser tube 17 from jet nozzle 21 expand in volume and condense at least in part upon coming in contact with the relatively cooler condensate thereby serving to preheat the condensate before return to the boiler. As the condensate and vapors pass downwardly through the convergent upper portion of the diffuser tube 17, the diminishing volume of the tube causes the fluid mixture to increase in velocity and decrease in pressure. After passing through the constricted throat of diffuser tube 17, the fluid mixture decreases in velocity and increases in pressure upon passage downwardly through the divergent lower portion of diffuser tube 17 whereby condensate is forced back into boiler 13 through the second condensate conduit 19 against the pressure in the boiler. Since the primary and secondary vapor conduits are lagged and the heat of the vapors impelling condensate in the condensate return means is used to preheat the condensate, there is very little loss in energy due to operation of the condensate return means. The pump does not depend upon a hydrostatic head of condensate for return to the boiler against boiler pressure and hence the pumping apparatus can be constructed in much more compact fashion than is possible with a gravity condensate return.

There are no moving parts to the entire pumping apparatus and hence the apparatus is not subject to mechanical failure. Upon increasing pressure in the boiler, the vapors evolved from nozzle 21 have increased initial pressure and velocity and hence provide greater pressure for returning condensate to the boiler whereby the condensate return means is automatically responsive to pressure changes in the boiler. The vacuum pumping apparatus embodying the invention can thereby be operated at high boiler pressures resulting in an increased pumping rate and the ability to operate against a higher fore-pressure.

While the invention has been described in considerable detail with reference to a preferred embodiment thereof, it will be understood that variations and modifications can be effected in the apparatus embodying the invention within the spirit and scope of the invention as illustrated in the drawing and described hereinabove and as defined in the appended claims.

What we claim is:

1. Vacuum pumping apparatus of the type wherein organic pump fluid vapors are passed through paired ejector and diffuser elements and

condensed, said apparatus comprising in combination vacuum pumping means including paired ejector and diffuser elements, a boiler positioned below and spaced from said vacuum pumping means, vapor-channeling means connecting said boiler and said ejector element, and means for returning condensate from said pumping means to said boiler against pressure in said boiler, said means for returning condensate comprising a downwardly directed diffuser tube between said pumping means and said boiler, a condensate return conduit connecting said pumping means with an upper portion of said diffuser tube, a second conduit connecting a lower portion of said diffuser tube with said boiler in a lower zone of said boiler below the normal liquid level in said boiler, jet nozzle means directed downwardly into said diffuser tube, and a vapor conduit connecting said jet nozzle means and said vapor-channeling means.

2. Vacuum pumping apparatus of the type wherein organic pump fluid vapors are passed through paired ejector and diffuser elements and condensed, said apparatus comprising in combination vacuum pumping means including an ejector element and a diffuser element arranged in pumping relation, said pumping means having an inlet port in a low pressure zone of said pumping means and having an exhaust port in a higher pressure zone of said pumping means, condenser means arranged in heat-conducting relation with said diffuser element and arranged for condensing organic pump fluid vapors passing through said diffuser element, a boiler positioned below and spaced from said pumping means, a primary vapor conduit connecting said boiler and said ejector element, and means for returning condensed pump fluid from said pumping means to said boiler against pressure in said boiler, said means for returning condensed pump fluid comprising a downwardly directed diffuser tube disposed between said pumping means and said boiler, said diffuser tube including a downwardly converging upper portion and a downwardly diverging lower portion, a condensate return conduit connecting said pumping means with said upper portion of said diffuser tube, a second conduit connecting said lower portion of said diffuser tube with said boiler, jet nozzle means directed downwardly into said upper portion of said diffuser tube, said condensate return conduit being connected to said diffuser tube at a zone not lower than said jet nozzle means, and a secondary vapor conduit of substantially

lesser cross-section than said primary vapor conduit and connecting said jet nozzle means and said primary vapor conduit.

3. Vacuum pumping apparatus of the type wherein organic pump fluid vapors are passed through ejector and diffuser elements arranged in pumping relation and condensed, said apparatus comprising in combination a generally horizontally disposed diffuser element having a convergent low pressure portion and a divergent high pressure portion, an ejector element directed into said convergent low pressure portion, a boiler spaced from and below said diffuser element, a primary vapor conduit connecting said boiler with said ejector element, an inlet port in the low pressure portion of said diffuser element, an outlet port in the high pressure portion of said diffuser element, a condenser coil for carrying cooling fluid disposed around said diffuser element in heat-conducting relation therewith, and means for returning condensed pump fluid from said diffuser element to said boiler against pressure in said boiler, said means comprising a generally vertically disposed diffuser tube positioned below said diffuser element and above said boiler and having a downwardly convergent upper portion and a downwardly divergent lower portion, a condensate conduit connecting said diffuser tube with said upper portion of said diffuser tube, a second condensate conduit connecting said lower portion of said diffuser tube with said boiler in a zone of said boiler below the normal liquid level in said boiler, a flared nozzle directed downwardly into said convergent upper portion of said diffuser tube, and a secondary vapor conduit of substantially lesser diameter than said primary vapor conduit connecting said flared nozzle with said primary vapor conduit, said first-named condensate conduit being connected to said diffuser tube at a zone not lower than said flared nozzle.
